UNITED STATES PATENT OFFICE.

JOSEPH HERBERT CHASE, OF BUFFALO, NEW YORK, ASSIGNOR TO THE CHASE & BAKER COMPANY, OF BUFFALO, NEW YORK, A CORPORATION OF NEW YORK.

AIR-GOVERNOR FOR MUSICAL INSTRUMENTS.

No. 849,050.

Specification of Letters Patent.

Patented April 2, 1907.

Application filed May 3, 1906. Serial No. 314,941.

To all whom it may concern:

Be it known that I, JOSEPH HERBERT CHASE, a citizen of the United States, residing at Buffalo, in the county of Erie and State of New York, have invented a new and useful Improvement in Air-Governors for Musical Instruments, of which the following is a specification.

In self-playing musical instruments in which the main bellows is operated by pedals and the music-sheet is propelled by an air or exhaust motor it is necessary to automatically control the air-current produced by the main bellows in order to insure a steady and uniform travel of the music-sheet notwithstanding variations in the bellows-section or air tension. It is also desirable after playing a piece of music to rewind the music-sheet at a comparatively high speed by allowing the main bellows to act upon the motor at its highest air tension.

It is the object of my invention to produce a reliable air-governor for this purpose which is simple and compact in construction and which can be easily applied to the main bellows.

In the accompanying drawings, consisting of two sheets, Figure 1 is a vertical section of the improved air-governor applied to the reservoir of a suction-bellows, showing the position of the movable parts while regulating the speed of the air-motor, the plane of the section being in line 1 1, Fig. 7. Fig. 2 is a similar section showing the position of the parts when the full suction of the bellows acts upon the motor in rewinding the music-sheet. Fig. 3 is a horizontal section in line 3 3, Fig. 1, looking upward. Fig. 4 is a horizontal section in line 4 4, Fig. 5, looking upward. Figs. 5, 6, and 7 are vertical sections in the correspondingly-numbered lines in Fig. 1. Fig. 8 is a side elevation of the air-governor.

Similar letters of reference indicate corresponding parts throughout the several views. A indicates the main suction-bellows of a piano-player or similar musical instrument, and A' the arm of its movable board, which is actuated by the usual pedals. (Not shown.) A² is the stationary air chamber or reservoir carrying the bellows A and connected therewith by the usual port a.

To the front side of the air-reservoir is ap-

plied the improved air-governor, which consists of a box or case containing a lower or outlet chamber B, which communicates with the air-reservoir by a port b in the front wall of the latter; an upper or inlet chamber C, provided at one end with an aperture c, with which is adapted to be connected the apparatus or appliance to be controlled by the governor, such as the air-motor which propels the music-sheet of a piano-player or self-playing musical instrument, and a chamber or connecting-passage D, which communicates with the chambers B C by ports e in the front wall of said chambers.

To the upper port f is applied a sliding throttle-valve g for manually controlling the speed of the motor and the tempo at which the music is played. This valve is operated by a rod h or any other suitable means. The port f may be of any suitable shape, but is preferably elongated and enlarged at one end, as shown. In the construction shown in the drawings it is formed in a wear-plate f' of harder wood than the body of the air-governor, the front wall of the chamber C being provided with a comparatively large aperture f'', which registers with the port f.

The port e is controlled by an automatic regulating-valve i, preferably arranged in the outlet-chamber B, so as to open with or in the direction of the suction-current. This valve is carried by a lever I, suitably fulcrumed within the chamber B and acted on by a spring i', which tends to open said valve.

J indicates a governing bellows or pneumatic having its fixed board secured to the front side of the chamber D, while its movable board acts through a rod or sticker j upon the lower arm of the lever I in such manner that when said bellows is collapsed it closes the valve i, while when it expands it allows the spring i' to open said valve. This rod passes through the connecting-chamber D.

As shown in Fig. 8, the governing-bellows is provided with a suitable expansion-spring J', which resists the inward or collapsing movement of its movable board. The governing-bellows communicates with the connecting-chamber D by an exhaust-port k and with the outer atmosphere by an air or flushing port l, as best shown in Fig. 4.

These ports are controlled by a sliding switch-valve *M*, which is arranged to close the flushing-port *l* when the exhaust-port *k* is opened, and vice versa. This valve, like the throttle-valve *g*, may be operated manually by a rod *m* or other suitable means.

When the instrument is at rest, the governing-bellows *J* is expanded, allowing the regulating-valve *i* to remain wide open.

10 When the instrument is to be played, the throttle-valve *g* is opened more or less, according to the desired tempo, and the switch-valve *M* is shifted to open the exhaust-port *k* and close the flushing-port *l*, as shown in Figs. 4 and 5. Upon now operating the main bellows *A* air is exhausted from the customary exhaust passage or chamber of the motor through the aperture *c*, inlet-chamber *C*, ports *f*, *f'*, connecting-chamber *D*, port *e*, outlet-chamber *B*, and port *b*. At the same

15 time air is exhausted from the governing-bellows *J* through the port *k*, thereby collapsing said bellows more or less, according to the resistance of its spring *J'* and the suction or air tension produced by the main bellows and causing the regulating-valve *i* to be closed to a corresponding extent. As the suction increases the regulating-valve restricts or cuts off the air-current through the port *e*, and as the suction diminishes the spring *J'* expands the governing-bellows and allows the valve to open farther, thus equalizing the suction or tension upon the air-motor and maintaining a practically uniform speed of the music-sheet notwithstanding variations in the air tension of the main bellows and regardless of the position of the tempo-regulating valve.

20 By properly tensioning the spring *J'* any desired degree of suction less than that of the main bellows suction may be obtained in the chamber *C* and the air-motor or other apparatus connected therewith.

When it is desired to operate the motor at 45 a high speed for quickly rewinding the music-sheet, the throttle-valve *g* is fully opened, and the switch-valve *M* is reversed to close the exhaust-port *k* and open the flushing-port *l*. This entirely cuts off the governing-bellows *J* from the influence of the suction-current and allows it to expand, permitting the regulating-valve *i* to open fully, as shown in Fig. 2, and allowing the air to be exhausted from the motor without restriction.

50 To prevent loss of air, the switch-valve *M* is made of such length that the exhaust-port *k* is fully closed before the flushing-port *l* is opened.

It will be observed that in this improved construction the air-current, whether controlled for uniformly propelling the music-sheet or unrestricted for quickly rewinding the sheet, passes through one and the same port *e*, thus simplifying the construction of the device.

The box or case *A*, containing the regulating-valve *i* and carrying the governing-bellows *J*, is preferably removably secured to the air-reservoir by screws, as shown, or other suitable fastenings, thus enabling the entire governing device to be readily removed for adjustment and repair and as easily applied or replaced.

By arranging the regulating-valve to close against the wind it opens instantly when released, avoiding the suction incident to a valve which opens against the wind.

75 While I have herein shown sliding throttle and switch valves and a pivoted regulating-valve, I do not wish to be limited to those particular constructions, as these parts and others may obviously be modified without departing from the scope and spirit of the invention.

I claim as my invention—

1. An air-governor, comprising a case having inlet and outlet chambers, a valve controlling the passage of the air from one of said chambers to the other, a governing-pneumatic controlling said valve, and means for establishing or cutting off communication between said pneumatic and said outlet-chamber at will, substantially as set forth. 85

2. An air-governor, comprising a case having inlet and outlet chambers, a valve controlling the passage of the air from one of said chambers to the other, a governing-pneumatic controlling said valve and communicating with said outlet-chamber by an exhaust-port and with the atmosphere by a flushing-port, and a switch-valve operating to close one of said ports when the other is opened, substantially as set forth. 95

3. An air-governor, comprising a case having inlet and outlet chambers, a manual throttle-valve for controlling the passage of the air from the inlet to the outlet chamber, a regulating-valve also controlling the passage of the air from the inlet to the outlet chamber, a governing-pneumatic controlling said regulating-valve and communicating normally with said outlet-chamber, and a valve for establishing or cutting off communication between said pneumatic and said outlet-chamber at will, substantially as set forth. 105

4. An air-governor comprising a case having inlet and outlet chambers, a chamber or passage connecting said chambers, a regulating-valve controlling the passage of the air from said connecting-chamber to said outlet-chamber, a governing-pneumatic controlling said valve, and means for establishing or cutting off communication between said pneumatic and said connecting-chamber at will, substantially as set forth. 115

5. An air-governor comprising a case having inlet and outlet chambers, a chamber or passage connecting said chambers, a regulating-valve controlling the passage of the

- air from said connecting-chamber to said outlet-chamber, a governing-pneumatic controlling said valve and communicating with said connecting-chamber by an exhaust-port 5 and with the atmosphere by a flushing-port, and a switch-valve operating to close said flushing-port when said exhaust-port is opened, and vice versa, substantially as set forth.
- 10 6. An air-governor comprising a case having inlet and outlet chambers, a chamber or passage connecting said chambers, a regulating-valve controlling the passage of the air from said connecting-chamber to said 15 outlet-chamber, a governing-pneumatic normally communicating with said connecting-chamber, and controlling said regulating-valve, and a throttle-valve controlling the passage of the air from said inlet-chamber to 20 said connecting-chamber, substantially as set forth.
- 10 7. An air-governor, comprising a case having inlet and outlet chambers, a chamber or passage connecting said chambers, a throttle- 25 valve controlling communication between said inlet-chamber and said connecting-chamber, a regulating-valve controlling communication between said connecting-chamber and said outlet-chamber, a governing-pneumatic 30 controlling said regulating-valve, and a switch-valve for establishing or cutting off communication between said pneumatic and said connecting-chamber, substantially as set forth.
8. An air-governor, comprising a case having 35 inlet and outlet chambers and a port or passage connecting the same, a regulating-valve applied to said port and opening in the direction of the air-current through the same, and a governing-pneumatic normally 40 communicating with said chambers and controlling said valve, substantially as set forth.
9. An air-governor comprising a case having 45 inlet and outlet chambers, a chamber or passage connecting the same, a lever arranged in said outlet-chamber, a valve carried by said lever and controlling the port between the outlet-chamber and the connecting-chamber, a governing-pneumatic normally 50 communicating with said connecting-chamber, and a sliding rod transmitting motion from the movable board of said pneumatic to said lever and passing through said connecting-chamber, substantially as set forth.

Witness my hand this 28th day of April, 1906.
